Carpenter Atty.

UNITED STATES PATENT OFFICE.

KARL M. HAMILTON, OF CHICAGO, ILLINOIS, ASSIGNOR TO CHICAGO-CLEVELAND CAR ROOFING COMPANY, OF CHICAGO, ILLINOIS, A CORPORATION OF ILLINOIS.

COMPOSITE CAR END.

1,297,153.

Specification of Letters Patent. Patented Mar. 11, 1919.

Application filed September 6, 1918. Serial No. 252,823.

To all whom it may concern:

Be it known that I, KARL M. HAMILTON, (assignor to Chicago-Cleveland Car Roofing Company, a corporation of Illinois,) a citizen of the United States, residing in Chicago, in the county of Cook and State of Illinois, have invented a new and useful Improvement in Composite Car Ends, of which the following is a specification.

10 My invention relates to car-end construction, and has for an object the provision of a composite end constituted partly of metal paneling and partly of wood paneling, with such paneling disposed in vertically extending sections and arranged to resist the end thrust of the load in the car and at the same time form a light and economical end structure; and the invention has for further objects such other advantages of structure and 20 function as may be found to obtain in the device hereinafter described and claimed.

In the accompanying drawings, forming a part of this specification, and which show a preferred form in which the invention may be embodied and exemplified, without being limited to such illustrative embodiment, Figure 1 is an elevation of the outside face of such end structure; Fig. 2 is a section on the line 2—2 of Fig. 1; Fig. 3 is a detail elevation of a modified application of the metallic paneling secured to the end posts; Fig. 4 is a section on the line 4—4 of Fig. 3; Fig. 5 is an enlarged section on the line 5—5 of Figs. 1 and 2; and Fig. 6 is an enlarged section on the line 6—6 of Fig. 3. Like reference numerals indicate like parts in all of the figures.

The middle vertical section of the end structure is constituted of the vertically corrugated metal paneling 10 applied upon the outer face of the end sheathing and having its side edges bolted to the end posts 11 and having its top edge bolted to the end plate and its bottom edge bolted to the end sill. 45 Between said end posts there are vertical filler-posts 16, each alined with an inwardly projecting corrugation of the metal paneling and filling the space between the end sheathing and the inner lining 15; and the 50 belt-rail 17 also occupies said space transverse of the said corrugations. On either side of said end posts 11, and extending from them laterally outward to the corner posts, there is wood paneling 12, forming the 55 lateral vertical sections of the end structure.

Corner strips 13 are bolted over the side edges of the wood paneling and around the corner posts, at about the middle of the height of the latter; and other corner strips 14 are similarly bolted over the lower corners of the wood paneling and around the lower ends of the corner posts. In the modification shown in Figs. 3, 4 and 6, the inner wood lining 15; of the car-end, extends across both the aforesaid wood paneling and 60 metal paneling and bears against the inner faces of the end posts 11 and of the corrugations of the said metal paneling.

Such arrangement of end posts, wood structure and metal paneling resists the 70 main strain of the end thrust of the load in the car; and the laterally disposed sections of the wood paneling sufficiently resist the remainder of such strain and at the same time lighten the end structure and 75 greatly economize the required employment of metal members in that structure.

I claim:

1. In a car-end, in combination: metallic plate paneling forming a vertical section of 80 the car end, to resist the center thrust of the load; and wood paneling forming the remaining body sections of the car-end on either side of said metallic section; substantially as specified.

2. In a car-end, in combination: corrugated metallic plate paneling forming a vertical section of the car end, to resist the center thrust of the load; and wood paneling forming the remaining body sections of the 90 car-end on either side of said metallic section; substantially as specified.

3. In a car-end, in combination: vertically corrugated metallic plate paneling forming a vertical section of the car end, to resist 95 the center thrust of the load; and wood paneling forming the remaining body sections of the car-end on either side of said metallic section; substantially as specified.

4. In a car-end, in combination: corrugated metal plate paneling forming a vertical section of the car end, to resist the center thrust of the load; wood paneling forming the remaining body sections of the car-end on either side of said middle metallic 105 sections; and an inner wood lining transmitting load-thrust strains to the inner ridges of said corrugations.

5. In a car-end, in combination: corner posts and intermediate end-posts; metallic 110

plate paneling forming a vertical section of the car end and laterally secured to the said end posts, to resist the center thrust of the load; and wood paneling forming the remaining body sections of the car-end on either side of said metallic section; substantially as specified.

6. In a car-end, in combination; corner-posts and intermediate end-posts; corrugated metallic plate paneling forming a vertical section of the car end and laterally secured to the said end-posts, to resist the center thrust of the load; wood paneling forming the remaining body sections of the car

end on either side of said middle metallic section and end-posts; and an inner wood lining transmitting load-thrust strains to the inner ridges of the aforesaid corrugations of the metallic paneling and against the inner faces of said end-posts; substantially as specified.

In testimony whereof I hereunto set my hand in the presence of two subscribing witnesses.

KARL M. HAMILTON.

Witnesses:

HENRY LOVE CLARKE,
ETHEL WOOD.
